UNITED STATES PATENT OFFICE.

FRANCIS HARRISON, OF LONDON, ENGLAND, ASSIGNOR TO THE ALADDIN RENEW ELECTRIC LAMP CORPORATION LIMITED, OF LONDON, ENGLAND.

ELECTRIC INCANDESCENT LAMP.

1,362,303.

Specification of Letters Patent. Patented Dec. 14, 1920.

Application filed July 8, 1919. Serial No. 309,361.

To all whom it may concern:

Be it known that I, FRANCIS HARRISON, a subject of the King of England, residing at London, England, have invented certain new and useful Improvements in Electric Incandescent Lamps, of which the following is a specification:

This invention relates to electric incandescent lamps and to a process and means for placing the filament of such lamps in position within the lamp in their repair. In British Patent No. 114464 such a process and means are disclosed, and the present invention is for an improved process and means of the same general character for placing a new filament in an old lamp without removing the bulb. It has been found in practice that the process and means described in detail in the aforesaid patent involve a somewhat undesirable degree of difficulty in the removal of the temporary supports from within the lamp and it is an object of the present invention to obviate the said difficulty by providing an improved process and means.

The present invention therefore provides a process for winding the filament upon permanent supports within an electric incandescent lamp for repairing the lamp, consisting in (a) removing the pip of the bulb and making a small opening at the bottom of the lamp by the use of a blow-pipe flame, (b) securing to the end of the central stem within the lamp below the permanent filament-hooks, by the aid of heat, a pin with a fusible head and a metal stalk to support a carrier, (c) mounting one or more temporary filament-hooks upon a carrier having a central tubular sleeve to slip on to and frictionally hold to the said stalk, (d) placing the said carrier upon the said stalk within the lamp, (e) subsequently winding the filament so that it engages the said temporary filament-hooks, setting it, disengaging it from the temporary filament-hooks and engaging it with the said permanent hooks and removing the temporary hooks with their carrier from within the lamp.

By way of illustrating the present invention one mode of carrying it into effect is now described in some detail with reference to the accompanying drawings, in which—

Figure 1 illustrates the support or downwardly directed stalk;

Fig. 2 shows the carrier with the temporary filament-hooks; 55

Fig. 3 shows a lamp with the pip end of the bulb open, and the support or downwardly directed stalk attached to the end of the central stem; and 60

Fig. 4 shows the carrier with the temporary filament-hooks in position upon the support or downwardly directed stalk.

A short length of nickel wire A is provided with a glass head B so that it has the 65 appearance of a short glass headed pin.

A small fiber disk C is prepared and fitted with a central tubular sleeve D extending at right-angles to the plane of the disk and of such a bore as to slip friction-tight on to the 70 nickel wire or pin A. Hooks of copper E are cemented to the fiber disk (for example by sealing-wax C¹), the hooks E being of such substance and dimensions as to constitute temporary filament-hooks stiffer than 75 the permanent lower ones F within the lamp.

An opening G is made in the pip end of the lamp, the diameter of the opening being quite small, in the neighborhood of between 80 $\frac{1}{4}$ and $\frac{3}{8}$ of an inch. A blow-pipe jet is applied to the bottom of the central glass stem H within the lamp to soften it and the nickel pin A is at the same time introduced by a suitable tool into the lamp through the 85 said hole G and fused on to the bottom of the stem H by means of its own glass head B.

The said temporary hooks E are then bent down upon their carrier to enable them to 90 be passed through the hole G and the carrier is slipped on to the pin A, its tubular sleeve D being threaded onto the pin A and pushed into gentle frictional engagement therewith, as shown in Fig. 4. The temporary hooks E are then bent so as to extend into close proximity with the permanent hooks F and the filament is threaded in the known manner upon these temporary hooks E and the permanent hooks J at the far end 100 of the central glass stem H, the ends of the filament being secured in the spring clips K K¹ illustrated in Fig. 3, and previously referred to in United States Patent No. 1,247,956. The remaining steps of setting 105 the filament, and transferring it to its permanent supports are those that are already known.

After these have been carried out the carrier (including the fiber disk C, tube D, cement C', and temporary hooks E) is withdrawn from the nickel pin A and out from the lamp through the hole G aforesaid. The nickel pin A is conveniently left secured to the end of the central stem H where it may serve for a subsequent renewal of the filament in the same manner.

10 Throughout this specification the expressions "upper" and "lower" and similar expressions relating to relative positions are employed on the supposition that the lamp is hanging with its cap uppermost and its 15 pip end downward.

The fact that the center stem of the lamp is of glass renders it desirable that the attachment of the pin to support the hook carrier shall be by fusion of glass in order that 20 it shall withstand temperature changes, such for example as occur during the setting of the filament. Similar considerations indicate the selection of nickel as the substance for the pin. It will be obvious, however, 25 that other materials may be employed provided they are such as will withstand the temperature changes to which they are subjected without the pin becoming separated from the central stem.

30 It will be appreciated that owing to the provision made for supporting the temporary hook carrier below the permanent hooks, the operation of withdrawing the former is rendered simple and substantially 35 such as to eliminate all danger of fouling either the filament after it has been transferred to the permanent supports, or the permanent supports themselves. The process is intended for repairing incandescent 40 lamps, and especially incandescent lamps whose filaments are to be of drawn wire.

What I claim as my invention and desire to secure by Letters Patent is:—

1. The hereindescribed process of winding 45 a metallic filament upon the permanent supports within an electric incandescent lamp to renew the lamp without removing the bulb, which comprises making a small opening at the pip of the bulb, securing to the 50 end of the central stem within the lamp below the permanent filament hooks by the

aid of heat a pin with a fusible head and a stalk to support a carrier, mounting temporary filament hooks upon a carrier having a central tubular sleeve to slip on to and frictionally hold to said stalk, placing said carrier upon said stalk within the lamp, subsequently winding the filament so that it engages said temporary filament hooks, setting the filament, disengaging it from the temporary filament hooks and engaging it with said permanent hooks and removing the temporary hooks with their carrier from within the lamp.

2. The hereindescribed process as claimed 65 in claim 1 in which the pin has a stalk of metal such as nickel.

3. The hereindescribed process as claimed in claim 1 in which the two free ends of the new filament are connected to the leading 70 in wires by closely coiled helices each of which grips between its convolutions one leading in wire and one end of the new filament.

4. The process of renewing lamp filaments 75 without removing the bulb, comprising making an opening in the bulb, securing to the stem within the bulb and adjacent the permanent filament hooks a pin adapted to receive and support a temporary carrier, 80 placing on said pin a temporary carrier provided with filament supports, winding the filament so that it engages said supports, setting the filament and then disengaging it from said supports and engaging it with the 85 permanent filament hooks, substantially as described.

5. The process of renewing lamp filaments without removing the bulb, comprising making an opening in the bulb, fusing to the 90 stem within the bulb and adjacent the permanent filament hooks a pin adapted to receive and support a temporary carrier, frictionally mounting on said pin a temporary carrier provided with filament supports, winding the filament so that it engages said supports, setting the filament and then disengaging it from said supports and engaging it with the permanent filament hooks, 95 substantially as described.

In testimony whereof I affix my signature.
FRANCIS HARRISON.
